UNITED STATES PATENT OFFICE.

EDWARD T. JOHNSON, OF GREENFIELD, MASSACHUSETTS.

COLLAPSIBLE CONTAINER.

Application filed July 19, 1926. Serial No. 123,318.

This invention relates to collapsible containers for the shipment of merchandise of various kinds and has for its principal object the provision of a collapsible crate or box 5 of firm and durable construction, comprising a plurality of interfitting members, constituting the bottom, sides and ends of the container, one or more of said members cooperating with the contents of the container to lock all the members in rigid position. Another object is to provide a knock-down box of this type, the several separable parts of which may be assembled flatwise in a compact bundle for transportation, thus 10 permitting successive uses of the same container with the consequent saving in box material. Further objects, including the elimination of the necessity of nails, screws or other fastenings for assembling the box 15 members, reside in the particular details of construction hereinafter described.

One particularly useful embodiment of the invention is illustrated in the accompanying drawings of a box adapted for the shipment of storage batteries for use in automobiles and in connection with radio receiving sets. These batteries are ordinarily shipped from the manufacturer to the dealer or distributor in individual containers, which 20 must be of firm and durable construction in order to prevent damage to the battery case or contents. The provision of a new container for each battery thus transported entails a considerable expense and results in 25 a substantial waste of box material; for the boxes heretofore used have been of such character that they could not be used for subsequent shipments or could not economically be returned to the sender for reshipment 30 because of their bulk. The collapsible box herein described possesses all the desirable features of indestructibility of the former containers, and in addition may be returned to the sender in a compact package 35 at slight expense to be used in transporting shipments of individual batteries.

In the drawings, illustrating a preferred form of any collapsible battery container,

Fig. 1 is a plan view of the assembled container or box, with a corner portion broken away;

Fig. 2 is a side elevation of the assembled

box, with a lower corner portion broken away;

Fig. 3 is an end view of the box;

55

Fig. 4 is an edge view of one of the side members of the box;

Fig. 5 is a plan view of the member shown in Fig. 4;

Fig. 6 is a plan view of the bottom member;

Fig. 7 is an edge view of the bottom member;

Fig. 8 is an elevation of an end frame;

Fig. 9 is a vertical section on the line 9—9 65 of Fig. 8;

Fig. 10 is a perspective view of an end locking member;

Fig. 11 is a plan view of a cover which may be used to close the top of the box; 70 and

Fig. 12 is a horizontal section on the line 12—12 of Fig. 11.

The collapsible container thus shown comprises a substantially rectangular box consisting essentially of a bottom member represented generally as A, a pair of similarly constructed side members B, identical end locking members C and a pair of end frames D, each member being composed of 75 a framework of relatively thin, but strong strips suitably joined together. The material from which said members may be fabricated may be of any suitably rigid material, such as metal, composition material, or wood 80 as illustrated. When disassembled these members may be readily laid substantially flatwise upon one another for convenient packaging; yet they may be quickly assembled into a container, the various portions 85 of each element abutting co-operating portions of an adjacent member, as hereinafter described, to constitute an interfitting structure adapted to hold a battery for shipment without the employment of nails or other 90 fastenings to connect the various members.

Although batteries are customarily shipped in a box without a cover in carload or truck shipments, a surrounding strap being employed to hold the battery in the open 100 box, a cover element E may be provided as desired for batteries or other merchandise.

The bottom member A consists of a pair of flat, relatively wide strips 13, joined to

gether but spaced apart by narrow cross cleats 14, nailed to the under side thereof intermediate the ends of strips 13. The top surface of the ends of each of the strips are 5 cut away at 15 to provide shoulders 16, to cooperate with the bottom edge of end locking members C, as hereafter explained.

Each of the side members B comprise a pair of longitudinal strips 17 held in spaced 10 apart parallel relation by two pairs of cross cleats 18 and 19 on their respective outer surfaces. Cleats 19 are fastened flush with the ends of strips 17 and are shorter than cleats 18, the outer corners of strips 17 being 15 cut away at 20, and cleats 19 being spaced from the respective cleats 18 a distance approximately equal to the width of one of the cleats which are preferably of the same thickness and width in each instance throughout 20 the constructing of the various members.

Locking members C each consist of wide vertical strips 21, connected by a wide horizontal strip 22 intermediate the ends of strips 21, so that either of the ends of the 25 strips 21, for example the ends 23 may fit the cut away portion 15 of bottom member A, with one side surface abutting shoulder 16.

The end frames D each comprise an open 30 rectangular frame composed of horizontal strips 24 and vertical strips 25 which may be connected at their abutting ends by tongue and groove joints. Horizontal strips 26 are also nailed across the top and bottom portions of this frame as strengthening members 35 and co-operating abutments for the locking member C. The strips 24, 25 and 26 are each preferably of the same width as the cleats referred to above, and the distance between the strips 26 should approximate 40 the length of the cleats 19 of member B.

In assembling the separate members into a box structure, the end frames D are placed in upright position as in Fig. 9, spaced from 45 each other so that the side members B may be inserted in place with the vertical strips 25 of member D fitting into the spaces between the respective strips 18 and 19 of member B (see Fig. 1). Bottom member A is then rested upon the bottom strips 24 of 50 frames D, the ends of the longitudinal strips 13 of member A abutting the cross strips 26 of end frames D, and the cleats 14 abutting and spacing apart said bottom strips 24, as shown in Fig. 2. Locking members 55 C may be then inserted in place, the respective bottom edges 23 of strips 21 fitting into the cut out portions 15 of the longitudinal strips 13 of bottom member A and between 60 the shoulders 16 and the cross strips 26 of the end frames as indicated in Fig. 2. The lower edge of horizontal strips 22 may rest on strips 13 to hold the locking members upright, but it is intended that the contents 65 of the box will keep said locking members

in position, the upper edges of strips 21 thereof being restrained from outward movement by the respective upper cross strips 26^a, and from vertical movement by upper strip 24.

It is thus apparent that, when the assembled box contains a battery or other merchandise between the longitudinal strips 22 of the locking members, the assembled members are held in rigid relation with respect to each other by the interfitting constructional details above described, without the employment of extraneous fastenings. It is also obvious that, if it be desired to have a completely enclosed container the open spaces in the structure illustrated may be closed by additional strips or cleats or by employing strips of greater width.

If it is desired to close the top of this collapsible box, a cover, of simple but unique construction, such as illustrated in Figs. 11 and 12, may be utilized. The cover E consists of two relatively wide, longitudinal strips 27, held in spaced parallel relation by cleats 28 nailed thereto, and a third longitudinal strip 29 fitting between, and slideable longitudinally of, the strips 27, a cross cleat 30 nailed to strip 29 holds strip 29 in position and slides upon the top surface of strips 27, the cleats 28 preventing upward movement of the ends of strip 29. The cleats 28 are spaced from the ends of strips 27, respectively a sufficient distance to permit said ends to be inserted under either of the upper cross strips 24^a, of end frames D.

In use, either end of the respective cover strips 27 may be so inserted and one end of the intermediate strip 29 may be slid under the similar strip 24^a at the opposite end of the box. It is contemplated that, when such a cover is used, it will be necessary to depress the box contents slightly when affixing the cover, so that frictional engagement between the strip ends and the end frame strips 24^a will hold the cover in place.

A box constructed as above set forth is especially adapted for the purpose described, but may be used for other purposes with but slight and obvious changes in details. It is also apparent that various modifications may be made in the construction shown without departing from the essence of my invention or defined in the following claims. It is contemplated, for example that the locking member, herein referred to as the end member D, may form a part of the side or the bottom of the box with slight modification in structure and arrangement, if desired. It is also contemplated that the assembled box may be of sufficient size to contain a plurality of batteries for shipment.

Having described my invention, what I claim as new and desire to secure by Letters Patent is:

1. A knockdown box comprising a bottom

- member, a pair of similar side members, a pair of similar substantially rectangular, end frames, and a pair of similar locking members, all arranged in interfitting relation to constitute a substantially rigid box structure, the end frames fitting around and enclosing the respective ends of said bottom and side members, and said locking members being arranged at the ends of the box structure within said frames and substantially at right angles to, and resting on, said bottom member, whereby the side members and bottom member are held in fixed position, within the end frames, removal of said locking members permitting ready separation of the other of said members from each other.
2. A knockdown box adapted for the shipment of storage battery cases comprising a bottom member, a pair of side members, a pair of substantially rectangular end frames, and a pair of locking members, each of said members being constructed of relatively thin, longitudinal, rigid strips and thin,

rigid cross cleats fastened thereto and all being arranged in interfitting relation to 25 constitute a substantially rigid box structure, the end frames enclosing the respective ends of the bottom and side members and the vertical strips of said frames between 30 cooperating cleats of the side frames, and said locking members being arranged within the plane of said end frames, the lower edges of the locking members engaging shoulders adjacent the respective ends of the bottom member, and the upper edges 35 thereof being held in place within the respective end frames by the battery box contained within the box structure, removal of the battery box and the locking members 40 permitting ready separation of the other members from each other, so that they may be packaged in a compact bundle for shipment.

In testimony whereof I affix my signature,

EDWARD T. JOHNSON.
